E. STEVENSON

BED TABLE

Filed March 27, 1923

E. STEVENSON Inventor

၃၃၁

William J. Jacobs

Attorney

UNITED STATES PATENT OFFICE.

EDWARD STEVENSON, OF MASON CITY, IOWA.

BED TABLE.

Application filed March 27, 1923. Serial No. 627,997.

To all whom it may concern:

Be it known that EDWARD STEVENSON, a citizen of the United States, residing at Mason City, in the county of Cerro Gordo and State of Iowa, has invented certain new and useful Improvements in Bed Tables, of which the following is a specification.

This invention relates to a bed table and has for its principal object to provide a device which is especially adapted for use by invalids.

A further object of the invention is to provide a bed table of the above mentioned character, which may be easily and quickly secured to the side rail of a bed and which may be swung over the bed when in use and adapted to swing away from the bed when not in use.

Another important object of the invention is to provide a bed table of the above mentioned character, which is simple in construction, inexpensive, strong, durable and further well adapted for the purposes for which it is designed.

Other objects and advantages of this invention will become apparent during the course of the following description.

In the accompanying drawings forming a part of this specification and in which like numerals designate like parts throughout the same:—

Figure 1 is a top plan view of my invention showing the same in operative position on a bed rail.

Figure 2 is a side elevation of the same with the bed rail shown in section.

Figure 3 is a front elevation of the bed table supporting means.

Figure 4 is a sectional view taken on line 4—4 of Fig. 2, and

Figure 5 is a section taken on line 5—5 of Fig. 2.

In the drawings wherein for the purpose of illustration is shown the preferred embodiment of my invention, the numeral 1 designates the angle iron side rail of a bed and adapted to be supported thereon is the U-shaped bracket 2. This U-shaped bracket 2 has its arms 3 and 4 respectively provided with downwardly extending flanges 5 and 6 respectively at the outer ends thereof for the purpose of engaging the inner side edges of the bed rail 1. It being further understood that the arms 3 and 4 of the U-shaped bracket 2 are adapted to extend over the top face of the angle iron bed rail 1.

For the purpose of holding the bracket 2 in position upon the bed rail 1 I provide a movable clamping member 7.

The arms 3 and 4 of the U-shaped bracket 2 are provided with the longitudinal slots 8 and 9 respectively and adapted to be received in the longitudinal slots 8 and 9 respectively are the locking screws 10 and 11 which are carried by the movable clamping member 7. The movable clamping member is formed of angle iron and is adapted to engage the side of the angle iron bed rail 1 in the manner as more clearly shown in Fig. 2 of the drawings. When the angle iron clamping member 7 is in engagement with the side of the angle iron bed rail 1 and is clamped thereto by means of the clamping screws 10 and 11, the U-shaped bracket 2 will be securely supported on the bed rail.

The crown or base portion 12 of the U-shaped bracket 2 is provided with an opening 13 and adapted to be received in this opening 13 is the headed pin 14. This pin 14 which extends vertically from the U-shaped bracket 2 furthermore provides a means for rotatably supporting the sleeve 15. The sleeve 15 which is rotatably supported upon the pin 14 is provided with a suitable socket 16 adjacent its lower end for the purpose of receiving the headed end 17 of a curved cylindrical rod 18.

This curved cylindrical rod 18 which is supported in the sleeve 15 is adapted to extend upwardly and inwardly from the bracket 2 and its outer free end receives the table 19 and this table 19 is held in proper position upon the upper end of the curved rod 18 by means of a clamping member 20.

For the purpose of holding the table 19 and the supporting rod 18 therefor in adjusted position, I provide the chain 21 which is secured to the upper end of the headed pin 14 and is adapted to engage the rod 18 at a point adjacent thereto and thereby hold the supporting rod in the proper position.

It will thus be seen from the foregoing description that a bed table has been provided which is especially adapted for use by invalids wherein the simplicity of the same renders it very useful and easily operated and can be detachably secured to a bed rail in any desired position.

From the foregoing description of the construction of my improved apparatus, it

will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to without departing from the spirit or sacrificing any of the principles of the invention.

What I claim as new and desire to secure by Letters Patent is:—

A bed table of the class described comprising a U-shaped bracket, having fixed 10 clamping members at the outer ends of the arms thereof to engage the inner side edge 15 of a bed rail, a movable clamping member

slidably mounted on the underside of said bracket, said movable clamping member adapted to engage the outer side of said bed rail, means for holding said clamping member in adjusted position whereby said bracket is secured to said bed rail, a pin extending vertically from the base of said U-shaped bracket, a sleeve rotatably mounted on said pin, said sleeve provided with a pocket in the lower portion thereof, a curved cylindrical rod having an enlarged head receivable in said socket, the opposite free end of said rod adapted to receive and support the table.

In testimony whereof I affix my signature.

ED. STEVENSON.
